US0D1075707S

(12) **United States Design Patent** (10) **Patent No.:** **US D1,075,707 S**
(45) **Date of Patent:** **** May 20, 2025**

(54) **MOBILE COMPUTING DEVICE**

(71) Applicant: **ZEBRA TECHNOLOGIES CORPORATION**, Lincolnshire, IL (US)

(72) Inventors: **Sunghun Lim**, Bethpage, NY (US); **Hui-Chi Kuo**, New Taipei (TW); **Dae Suk Noh**, Vernon Hills, IL (US); **Mu-Kai Shen**, Taipei (TW)

(73) Assignee: **Zebra Technologies Corporation**, Lincolnshire, IL (US)

(**) Term: **15 Years**

(21) Appl. No.: **29/900,842**

(22) Filed: **Aug. 25, 2023**

Related U.S. Application Data

(63) Continuation of application No. 29/725,704, filed on Feb. 26, 2020, now Pat. No. Des. 1,001,093.

CLAIM

The ornamental design for a mobile computing device as shown and described.

DESCRIPTION

FIG. 1 is a first perspective view of a mobile computing device;

FIG. 2 is a second perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines in the drawings illustrate portions of the mobile computing device that form no part of the claimed design.

1 Claim, 7 Drawing Sheets
